UNITED STATES PATENT OFFICE.

WILLIAM CHURCHILL, OF CORNING, NEW YORK, AND ALEXANDER H. RUDD, OF MEDIA,
PENNSYLVANIA, ASSIGNEES TO THE POSITION-LIGHT SIGNAL COMPANY, A CORPO-
RATION OF MAINE.

SIGNALING SYSTEM.

1,175,339.

Specification of Letters Patent. Patented Mar. 14, 1916.

Application filed July 13, 1914. Serial No. 850,817.

To all whom it may concern:

Be it known that we, WILLIAM CHURCHILL, a citizen of the United States, residing at Corning, county of Steuben, and State of New York, and ALEXANDER H. RUDD, a citizen of the United States, residing at Media, county of Delaware, and State of Pennsylvania, have invented certain new and useful Improvements in Signaling Systems, of which the following is a specification.

As is well known, the system in common use to-day of transmitting intelligence and orders to trains, consists in the use of semaphore arms or disks by day, and colored lights by night, each position of the arm, and each color of the lights or disks having its peculiar signification such as stop, caution, or proceed. This difference in the method of signaling by day and night, necessitates two signaling apparatus for each indication to be given at each point, and necessitates the train-men remembering the signification of each position of the arm and each color. The semaphore arms are objectionable, in that they are moving parts liable to get out of order, in spite of the ingenuity that has been expended on their construction. The use of different colors for signaling is objectionable, in that color indications demand an absorption of colors other than that to be transmitted, and hence a reduction in the intensity of the beam.

We propose to avoid all of these defects as well as others inherent in the present signaling practice by using lights both as day and night signals, the indication being given by the relative position of the lights. Thus the ordinary (proceed) indication will be given by a series of lights or light-emissive surfaces arranged one above the other, while the stop-indication will be given by a series of such surfaces arranged side by side. The result of such an arrangement of individual lights or light-emissive surfaces when their intensity is properly proportioned to the atmospheric illumination and to their relative arrangement, is to produce the effect to the eye of an elongated illuminated area which will be horizontal or vertical or inclined according to the arrangement of the lights. If the intensity of illumination of the light sources is sufficiently great, the indication can be read at a great distance upon a suitable back-ground which we by preference provide, even though the sky be

brilliantly illuminated. However, we have found that this illumination which is sufficiently intense for day use, may be so brilliant at night as to obscure the indication intended to be transmitted, and instead of giving an elongated illuminated area, will, at a distance, give the effect of an area more or less elliptical or circular, and liable to be misread. We therefore preferably provide means for reducing the intensity of illumination of the several light-emissive surfaces for night signaling.

We have further provided means by which a signaling system such as above indicated is adapted for the severe conditions of use to which it must be placed, and caused with a minimum intensity of light to give a maximum efficiency at the points needed, and by which "phantom" signals will, at the same time be prevented.

Referring to the accompanying drawings, in which corresponding parts are designated by corresponding marks of reference. Figure 1 is a front elevation of a signal casing, constructed in accordance with this invention; Fig. 2 is a corresponding view of a modified form of casing; Fig. 3 is a fragmental vertical section taken on either Figs. 1 or 2, showing the relative location of the lamps, the reflectors and the lenses. Fig. 4 is a diagram representing the wiring of a signal such as shown in Figs. 1 or 2. Fig. 5 is a view showing a lamp and its mounting, the parts being shown slightly separated for purpose of illustration.

In carrying out our invention, we locate at suitable points adjacent to the tracks, signaling casings which may take the form either of a substantially circular box, or of a cross frame having arms corresponding to the position which it is intended that the signaling indications should have, as is shown, respectively, in Figs. 1 and 2. In the first case, namely that shown in Fig. 1, the face of the casing A is provided with one or more series of rows of light-emissive sources 1, 1¹, which are in the form of lenses, according to the number of indications which are to be given. The figure represents a signal having the stop (horizontal), proceed (vertical), and caution (diagonal upper quadrant) indication, all of the lens rows intersecting at a common point which, by preference is not at the end lens of any row, but at a lens 1¹, which is intermediate

in a row. Behind each lens is an appropriate light source, and the lights in the several rows are so wired that each row of lenses can be illuminated at will, or controlled by ordinary track-circuit for that purpose, to convey the desired indication. The lights of each row are by preference (except the common light 1^a) contained in a closed box 1^b, or housing (shown dotted in Fig. 1), located on the back of the casing to protect the lamps, and shield the lenses of each row from any light in their rear, except that from the lamps of the row in which they belong.

15 In Fig. 2, instead of the casing previously described, the casing takes the form of cross frames having three arms A, having the horizontal, vertical and upper quadrant positions, respectively, each of which carries a 20 row of lenses illuminated as before. It is obvious that many modifications can be made of the relative location of the angular position of the rows of lenses, and of their relative position to each other, and of their 25 number, and that the number of indications is not restricted to the three names or to associations given. In either case, the frame is preferably painted black; and affords a back-ground against which the light 30 indication is seen. This invention, however, is not in any way limited to the form of casting or casings for the light sources and the above descriptions have been given merely as embodying practical embodiments of it.

35 The conditions to be met in signaling by day and night by the illuminated field produced as above described are somewhat peculiar, and therefore we have found it advantageous to use the arrangement of lenses, 40 and light sources shown in Fig. 3. In this figure, the lens 1 is of an inverted type and is protected by the cover-glass 3, the lens itself being, by preference of the type which has its anterior face formed by a series of 45 zones and having its zones on its horizontal section, and on its upper part or quadrant struck with curves of less radii than on its lower part or quadrant, whereby its maximum of divergence is from its lower quadrant downwardly. It is, of course, necessary to provide a downward divergence in order that the beams projected by the lenses be visible, not only at a distance, but close up under the signal. To provide for visibility, both at a distance from, and when close to the signal, we also provide a spherical reflector 4 which is located above the source of illumination, it being, by preference, so calculated, and so located that all of the light 55 rays reflected therefrom on passing through the lens are deflected downwardly at more or less of an angle to the horizontal, the angle being, by preference as great as possible.

60 The relative arrangement of the lamps 5

and lens is an installation which we have found satisfactory such that the upper divergence of the rays are practically zero; that the side divergence is about five degrees on each side of the principal axis of 70 the lens; that the downward divergence due to lights falling directly on the rear surface of the lens from the source of light is about seventeen degrees, while the light reflected from the light source by the reflector passes 75 through the lens in such direction that it is projected downwardly at an angle of between seventeen and forty-six degrees to the principal focal axis of the lens, this providing for indications to train-men close under 80 the signal.

The source of illumination used is, by preference an incandescent electric lamp having a filament 5^a which is in the form of a spiral to produce the maximum illumination for a given length, and which, by preference has its filament arranged horizontally so that such divergence as may arise from the illumination not being localized at the principal focus of the lens will be a horizontal divergence. Inasmuch as the conditions demand for a proper vertical divergence a close adjustment of the lamp vertically, we prefer to mount lamps on vertically adjustable mountings, such for instance as those shown in Fig. 5. In this figure, the lamp has upon its base, the metallic collar 6, having diametrical pins 7 adapted to enter vertical slots 8 cut in a spring sleeve 9, in which sleeve the lamp may be adjusted vertically 100 by sliding it up and down until a given distance is obtained between the filament of the lamp and pins 10 projecting from the outside of the sleeve. Such sleeve may be then inserted in the base 11 provided with the 105 bayonet slot 11^a, by which the lamp will be positioned, and which will firmly clamp the sleeve upon the lamp collar. This provides a convenient means for overcoming irregularities of elevation in the sealing in of the 110 filaments. We further prefer to use yellow glass of the character known to the trade as "Noglare", as the material for the cover glass. As is well known this glass cuts down the blue and violet rays from the light 115 source, and we have found its use markedly advantageous in rendering the position indications more distinct, by preventing the loss of direction of the rows of light source, and this without materially reducing the visible 120 intensity of the signaling lights in the day time.

In practice, we have found that with the semaphore lens having an aperture of five inches, with a Noglare cover of one-quarter 125 of an inch thick, with a source of illumination behind each lens equivalent to about three candle power, and with four of such lights arranged in a row at eighteen inches apart from center to center, good day-light 130

indications are produced while the same constants are suitable for night use for the candle power of each source reduced to about one-quarter of a candle-power. The reason 5 for the reduction of candle power at night is that with the more powerful illumination necessary for day-light signaling, the light-emissive source may under certain conditions merge into one circular body of illumination when viewed from a distance at 10 night, while if reduced to the figures last given, the field of illumination appears as an elongated bar.

With the arrangement of the lamps and 15 lenses above indicated, all of the lamps of a signal casing are connected on their one side to a conductor 12, and all the lamps of each row, except the common lamp, have their opposite sides connected to independent 20 wires 13^a, 13^b and 13^c, respectively, while the common lamp has its other terminal connected to the wire 13^d. The wires 13^a, 13^b and 13^c are connected to one terminal of a variable potential source 14 by means of 25 switches 15 and 16, while the wire 13^d from the common light, may be directly connected to the same terminal of the source. From the source current flows through the common lamp wire 13^d, and the wires 13^a, 13^b, 30 and 13^c, respectively, through the lamps and the common feed wire 12 back to battery preferably by an alternative circuit to be hereinafter described. The switches 15 and 35 16 may be either manually controlled by an operator in a signaling-tower, or may be relay-contacts, as shown, controlled by a control-circuit 21 which in turn may be controlled by track circuits. In the arrangement shown, the circuit 21 is controlled by 40 two track magnets 21^a and 21^b in different blocks of the track, and contains the magnet 21^c of the switch 15. The switch 16 is controlled by the track magnet 21^a. Such relays are standard pieces of signal construction, and need no elaboration here.

The main lighting circuit, that is to say, the circuit to which the wire 12, 13^a, 13^b, 13^c and 13^d are connected, is, by preference, adapted to be fed by currents of different 50 potentials to provide for the differences in illuminations necessary to day and night signaling; and it is obvious that the lamps of a plurality of signal casings located at different points along the way may be fed 55 from a common source of variable potential, and the potential supplied to the lamps of such signals may be varied simultaneously by a variation in the potential of the source. This may be conveniently accomplished by 60 providing a relay 17 in a control circuit 18 adapted to actuate a switch 19 connected with the common feed 12, and to throw it to the one or the other of two contact points 20, 20^a, one of which is connected to the opposite pole of the battery 14, from the pole

to which the wires 13^a, 13^c and 13^d are connected, and the other of which is connected to an intermediate point at that battery. Thus, in the installation before described, we made use of a total battery voltage of 11 70 volts for day-light signaling, and of three volts for night-signaling. The switch 19 may obviously be handled by a control-circuit 18 which may extend through a considerable length of road, or may be local to 75 each signal station and be controlled from a central station, or by an operator at each signal when it is desired to shift the voltage. It is obvious, however, that in lieu of using a battery any convenient variable source or 80 sources may be employed, and that the light-wiring for each signal may be connected with a line extending along the right of way, and upon which variable voltage may be impressed at will.

The use of a common lamp is an advantage, in that such lamp may be kept constantly burning, and need not be extinguished or lighted on each change of the signaling providing an additional light-emissive point in any row of lights that may be used. This is an advantage in reducing the amount of current to be controlled by the circuit-controlling relays which are necessarily of delicate construction liable to 95 be damaged upon the passage of excessive current. Each cover glass is by preference protected by a hood 23 to protect it from light from the sky.

Having thus described our invention 100 what we claim and desire to secure by Letters Patent is:—

1. In a system of light-signaling for day and night, the combination with a plurality of light-emissive surfaces arranged in a 105 row according to the indication to be given, means for illuminating such surfaces, and means for varying the illumination of such surfaces day and night.

2. In a signaling system, the combination 110 with emissive surfaces arranged in a plurality of rows, and located at each signal point, of an electric lamp behind each emissive surface, an electric circuit supplying current to the lamps of the several 115 signaling points, means for selecting the lamps at each signaling point to be illuminated, and means for varying the potential supplied to the lighting circuit.

3. In a signal system for day and night signaling, the combination with a plurality of light-emissive surfaces arranged in rows according to the indication to be given, of means for selecting the row of surfaces to be illuminated, and a dark back-ground 125 located behind the surfaces against which they are contrasted when illuminated for day-signaling.

4. In a signaling system for day and night signaling, the combination with a 130

- plurality of light units arranged in rows according to the indications to be given, and suitably spaced from each other, each unit including a lamp and a lens, and means 5 for varying the intensity of illumination of the units in a selected row as a whole, in accordance with atmospheric conditions, to cause the units of such row to appear as a single elongated illuminated area.
10. 5. In a signaling system for day and night signaling, the combination with a plurality of light units arranged in rows according to the indications to be given, and suitably spaced from each other, each 15 unit including a lamp and a lens, and a cover glass transmitting light substantially free from blue and violet rays.
6. In a signaling system for day and night signaling, the combination with a 20 plurality of light units arranged in rows according to the indications to be given, each unit including a lamp and a lens, of a dark back-ground behind the units, the lenses being of such size and so spaced and 25 the lamps being of such intensity as to cause the units of a row when illuminated by their lamps to appear as an elongated illuminated area against the back-ground, and means for varying the intensity of the 30 lamps in any row in accordance with atmospheric illumination to cause the units thereof to appear as an elongated illuminated area.
7. In a light-signaling system, the combination with a plurality of light-emissive 35 surfaces arranged in rows, one of such emissive surfaces being common to two or more rows, lamps for illuminating such surfaces, and means for constantly feeding current to the common lamp, and means 40 for selecting the other lamps in such rows as required.
8. In a light-signaling system, the combination with a plurality of light-emissive surfaces arranged in a row according to the 45 indication to be given, and means for cutting down the blue and violet rays from such light surfaces.
9. In a light-signaling system, the combination with a plurality of surfaces ar- 50 ranged in rows according to the indication to be given, and emitting light substantially free from blue and violet rays.
10. In a light-signaling system for day and night, the combination with a plurality 55 of light-emissive surfaces arranged in a row according to the indication to be given, and emitting light substantially free from blue and violet rays, and means for varying the illumination of such surfaces day and 60 night.
